UNITED STATES PATENT OFFICE.

ALBERT COWELL, OF KIDDERMINSTER, ENGLAND.

DESIGN FOR A CARPET-PATTERN.

Specification forming part of Design No. 5,709, dated March 26, 1872.

To all whom it may concern:

Be it known that I, ALBERT COWELL, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of the specification.

This invention relates to a new design of the scroll which constitutes the ground-work of a carpet; and also to that of a border for the carpet, both of which features are fully and clearly represented in the photograph.

The border is composed of several narrow outer strips or bands, of a main wider band, wherein successive and connected branches of flowers are arranged, as shown.

I claim as my invention—
1. The design for the ground-work of a carpet, as shown.
2. The design for the border of a carpet, as shown.

ALBERT COWELL.
